KNITTED FABRIC

Robert Evan Davis, Jr., Fort Payne, Ala., assignee to Interwoven Stocking Company, New Brunswick, N. J., a corporation of New Jersey

Application February 24, 1938, Serial No. 192,230

22 Claims. (Cl. 66—172)

My invention consists in the novel features hereinafter described, reference being had to the accompanying drawings which illustrate two embodiments of the same, selected by me for purposes of illustration, and the said invention is fully disclosed in the following description and claims.

In the manufacture of plain knit hosiery, and particularly in the manufacture of socks and anklets, it has been customary for many years to provide the upper part of the leg portion with what is termed a "top" formed of rib knitting of several inches in length, in order to provide a form fitting effect, the tubular rib knit portion having a smaller diameter and much greater elasticity than the plain knit fabric forming the main portion of the leg and containing the same number of stitches in the consecutive courses. This ordinarily necessitated knitting the rib tops on a rib knitting machine of some kind, then transferring the last row of stitches of the rib top to the single circular series of needles of a plain knitting machine, and then knitting the leg, heel, foot and toe of the stocking. This transfer involved the employment of highly skilled labor and added materially to the expense of the goods.

The object of my invention is to produce on a single machine, that is a plain knitting machine, by continuous operation, an entire stocking having a top of reduced diameter, obtained by forming stitches or wales on less than all of the needles, and preferably on every other needle of the circular series, and by the incorporation of an elastic thread of rubber or the well known Lastex in certain of the courses of stitches so formed, the elastic thread being fed under sufficient tension so that when the fabric is removed from the knitting needles, the elastic thread will draw the adjacent wales so formed on the alternate needles into juxtaposition to produce a smooth faced plain knit fabric of much less diameter than the plain knit fabric knit on all the needles of the same machine, said stocking having the leg and foot formed of courses of stitches equal in number to the number of needles in the machine and knit together with the heel and toe pockets in the usual manner and integral with the top of reduced diameter. The elastic thread is incorporated in the top by knitting it on the selected needles, less than the entire number, and preferably every other needle, upon which the top is formed, in selected courses of the top, spaced from each other by intervening courses which do not contain the elastic thread, the elastic thread in the stitches of the several courses con-

taining it straightening out in the fabric by reason of the tension under which the elastic thread is fed, and tending to bring together the preceding and succeeding courses formed entirely of body thread, and thus forming horizontally separated annular beads on the inner face of the fabric. These horizontal beads tend to impress themselves into the skin of the wearer when the stocking is worn, and being separated over such a large area, will support the top firmly on the leg and hold the leg of the stocking against any tendency to work downwards, without inconvenience or discomfort to the wearer. My improved stocking, therefore, provides a form fitting top of diameter smaller than that of the leg of the stocking and sufficiently elastic to permit the stocking to be drawn on over the heel, and also provides a self-supporting function, which enables it to be worn without garters or other extraneous supports.

My improved process can be carried out and my improved stocking and fabric can be produced by hand, but it is ordinarily carried out by a circular knitting machine, preferably what is termed a stocking knitter, and the successive courses of the top, leg and foot of the stocking may be formed of a plurality of courses knit simultaneously at a single revolution of the machine, or it may be formed by a plurality of successive courses, each knit by a single revolution of the machine, as may be preferred. Where multiple course knitting is employed, the knitting machine will be provided with a plurality of knitting cams located at different positions around the needle cylinder, each having associated with it mechanism for feeding a thread or threads separately during a single revolution of the machine, one of said knitting cams having associated with it a feeding finger for feeding the elastic thread, which may be thrown into and out of operation, as well as a similar thread feeding finger for one of the body threads, and the fabric produced in this manner will be formed of successive courses, the stitches of each of which will be knit into the stitches of a preceding and succeeding course formed of a different thread. Where my invention is carried out by single course knitting with a single knitting cam, all of the consecutive courses except those courses in the top, which are formed of elastic thread, will ordinarily contain stitches formed from the same thread or threads, it being understood that in either case the feed fingers may be provided in multiple to permit the substitution of threads of different colors or of different ma-

States filed on the 3rd day of March, 1938, and given Serial No. 193,622, and I have illustrated diagrammatically in Figs. 2 and 6 the arrangement of knitting cams and their associated thread feed fingers, for convenience in describing the process and product. This machine is the well known Banner machine manufactured by the Hemphill Company of Pawtucket, R. I., with certain changes and modifications fully disclosed in my companion application, the details of which are not necessary to an understanding of my present invention.

As indicated in Figs. 7 to 8a, the needles are divided in the usual manner into those having short butts, indicated at 1a in Figs. 7 and 7a, and those having long butts, indicated at 8a in Figs. 8 and 8a, the short butt needles extending half way around the cylinder and cooperating with the usual picker mechanism to effect narrowing 20 and widening. Certain of the long butt needles, as well as the short butt needles are provided above the butt with a shoulder, as indicated at 7b and 8b in Figs. 7 and 8, which are of less length in a radial direction than the needle butts 1a and 25 8a. I prefer to place these shouldered needles and plain needles, both of the long butt and short butt series, alternately in the cylinder, although I do not wish to be limited to that arrangement. The cam ring, indicated at 14 in Fig. 6, is provided with a main knitting cam mechanism of ordinary form, comprising the knitting cam 9 and the associated cam elements 9a, 9b, 9c, for actuating the needles during both circular and reciprocating work, in a well known way, and the 30 cam ring is further provided in this instance with three auxiliary knitting cams 18, 19 and 20, arranged at different points around the needle circle, as indicated for example in Fig. 2. Each of the auxiliary cams is movable into and out of operative position, preferably in radial directions, 35 although this is not essential.

Associated with the main knitting cam, which is located adjacent to the throat plate, are the usual plurality of thread feed fingers, one of which is indicated at 10, which is adapted to feed the elastic thread 1 to the hooks of the selected or non-shouldered alternate needles when they are raised above the adjacent needles. The elastic thread is fed to the finger 10 and to the needles 40 under appreciable tension, sufficient to draw together the wales of the fabric which, as will be hereinafter described, are formed only on the selected alternate needles. Any suitable form of tension device may be employed, and I have not 45 herein shown any particular device for that purpose. The usual form of friction plates held together by a spring capable of adjustment may be employed. The needle selection is effected by the main knitting cam, which is in position to engage the shoulders of the non-selected needles and the butts of the selected needles, which will necessarily draw down the non-selected or shouldered needles below the position occupied by the selected needles at the feeding point, as clearly 50 indicated in Fig. 6. At the throat there is also provided one or more thread guides for body thread, one of which is indicated at 12 for feeding a body thread, indicated at 1a, to all of the needles at a lower level than that of the finger 55 10 when in operative position, the operative position of finger 12 being indicated in dotted lines. These thread fingers 10 and 12 are independently movable into and out of operation, and when one is in operative position the other is in inoperative 60 position in carrying out my present invention.

For convenience of description I have indicated in Fig. 6 the main knitting cam and associated thread feed fingers as knitting station No. 1. The auxiliary knitting cams 18, 19 and 20 when in operative position do not project inwardly far enough to operatively engage the shoulders 1b, 25 8b, but will engage the butts of both long and short needles and will operate all needles in the same manner. In association with auxiliary cam 18, there is provided a thread finger 21 for feeding inelastic or body thread 2 to all of the needles and constituting with the knitting cam 18 knitting station No. 2. The auxiliary knitting cam 19 is provided with an associated thread feed finger 22 for feeding a body thread 3 to all the needles 15 and constitutes with the cam 19, knitting station No. 3. Associated with knitting cam 20 is a thread feed finger 23 for feeding a body thread 4 to all of the needles and constituting, together with the cam 20, knitting station No. 4. Means (not 20 shown) are provided in connection with each of the auxiliary knitting cams for throwing said cams and their associated thread feeding means simultaneously into and out of operative position. While I have shown in Fig. 6 only one 25 thread feed finger for body thread at each knitting station, it will be understood that additional thread fingers may be provided carrying body threads of different colors or of different character for purposes of striping or reinforcing, as 30 will be readily understood. It will be obvious that multiple knitting may be carried out with two, three or four threads, as may be desired.

The manner of carrying my process into effect 35 by multiple course knitting is illustrated diagrammatically in detail in Figs. 9 to 17 inclusive, assuming that one course of stitches of elastic thread and three courses of stitches of inelastic or body thread are to be formed in each revolution of the machine. For convenience of explanation I have assumed in Fig. 9 that three courses of stitches with the body threads 2, 3 and 4 have been formed and that the stitches of body thread 4 are held on each of the needles as they approach the first knitting station. At this point 40 the draw-down portions of the main knitting cam will engage the shoulders of the non-selected needles and draw them down to a greater extent than the selected non-shouldered needles, the hooks of which will therefore be in a higher plane 50 at the feed point adjacent to their feed finger 10 than the hooks of the intervening non-selected needles. The selected alternate needles will receive the elastic thread 1, thread finger 12 being in inoperative position as shown in Fig. 6, and the selected needles only will draw down loops of elastic thread 1 through the stitches of the preceding course formed of body thread 4, as indicated in Fig. 10, while the non-selected needles which do not receive the elastic thread 1 will cast 55 off their loops of thread 4, which will therefore unravel and straighten out, together with the corresponding loops of the preceding courses formed by body threads 3 and 2, forming floats, as clearly indicated in Fig. 11, between the wales 60 formed by the selected needles. All the needles will then be raised as indicated in Fig. 11, before coming to knitting station No. 2, the selected needles, holding loops of elastic thread 1 and the intervening needles being bare, and all of the 65 needles will receive the body thread 2 from the thread guide 21, and will be drawn down by the auxiliary knitting cam 18, as shown in Fig. 12. The selected needles will draw stitches of thread 2 through the stitches of the preceding course 70 75

formed by the elastic thread 1, while the intervening needles will merely draw down the thread without forming a stitch. The needles are then raised before reaching the third knitting station 5 and receive another body thread 3, as indicated in Fig. 13, from thread feed finger 22, and are drawn down by the auxiliary knitting cam 18, as indicated in Fig. 14, the selected needles drawing stitches of the thread 3 through the stitches 10 of the preceding course, and the intervening needles drawing stitches through the loops of thread 2 in the preceding course. The needles are then raised and pass to the fourth knitting station, where they receive the body thread 4 15 from thread feed finger 23, and are all drawn down by the auxiliary knitting cam 20, the selected needles again drawing stitches of the thread 4 through the stitches of the preceding course and the intervening needles also drawing 20 stitches of the body thread 3 through the stitches of the preceding course formed by body thread 3. The needles then pass to the first station again, as indicated in Fig. 9, where the selected needles are raised and only the selected needles receive 25 the elastic thread 1, and being drawn down as indicated in Fig. 10, the selected needles form alternate stitches of the elastic thread 1, while the intervening needles cast off their stitches, permitting the corresponding stitches of the preceding courses to again unravel and form floats, as previously described, and the operation is repeated in every revolution of the machine, throughout the top.

From the foregoing explanation it will be seen 35 that in knitting the top fabric, separated vertical wales will be formed by the selected or non-shouldered needles only, making the number of stitches in each course in this instance half the entire number of needles, and these wales will 40 be connected by horizontal floats produced by the unraveling of the intermediate stitches of body thread formed on the intervening needles, but permitted to ravel out at each course of the elastic thread 1, in the manner described.

45 The floats in every fourth course will be of the elastic thread 1, and as the elastic thread is fed under suitable tension as the fabric leaves the needles, the separated wales will be drawn together at the elastic courses and also between the elastic courses, the reduced number of stitches 50 in the fabric tending to elongate somewhat and take up portions of the floats of inelastic thread, and thus producing a plain knit fabric having a smooth outer face and composed of half the 55 number of stitches in each course than would ordinarily be made if stitches had been formed by all the needles.

I term this fabric a tubular plain knit alternate drop stitch fabric as it is formed by alternate needles of the machine, the intervening 60 stitches which have been formed are permitted to unravel or drop, and are therefore only represented by connecting floats in the fabric.

In the upper part of Fig. 18 I have shown, 65 greatly magnified, the alternate drop stitch fabric as it would appear theoretically if it remained in the condition in which it is knit. The tension of the elastic thread 1, however, causes it to straighten out in the fabric, thus 70 practically eliminating the loops formed by the elastic thread and distorting the stitches of the preceding and succeeding course formed of elastic thread, in the manner indicated in the upper part of Fig. 19. At the same time the tension 75 of the elastic thread will draw the fabric to-

gether laterally, as before described, and produce a fabric of reduced diameter. Fig. 20 diagrammatically shows the drawing-in of the alternate drop stitch fabric laterally, so that the wales will be brought substantially as close together 5 as adjacent wales of ordinary plain knitting, as shown at the top of said figure. This figure, as before stated, is merely diagrammatic, and shows the alternate drop stitch fabric forming the top of a stocking, united with a plain knit 10 leg knit on all the needles with inelastic thread only, and this figure was drawn in this manner to illustrate the continuity of the wales of the alternate drop stitch fabric top with the alternate wales of the plain knit leg. As a matter of 15 fact, all of the wales of the alternate drop stitch fabric will be drawn close together when the fabric is released from the needles, and this will naturally produce gathers or wrinkles in the plain knit leg fabric where they join the top, 20 as indicated at a, in Fig. 1. In actual practice, the stitches of the alternate drop stitch fabric tend to enlarge slightly when the fabric is contracted laterally by the elastic threads and shorten the intervening floated portions of the 25 inelastic thread between the wales. In the courses preceding and succeeding the elastic thread, however, the distortion of the stitches by the straightening out of the elastic tends to overcome this tendency, but in any intermediate 30 courses other than those with which the elastic thread is interknit the stitches will not be taken up vertically in this manner, and will result in somewhat elongated stitches which produce an 35 ornamental lacy effect in the finished fabric.

Thus, in Fig. 20 for example, it will be noted with special reference to the upper portion of the figure, that the stitches formed by the threads 4 and 2 and indicated at s, will not be lengthened vertically, due to their interknitting with 40 the elastic thread 1, while the stitches indicated at s', which are formed of the thread 3 and lie intermediate the courses formed by the threads 2 and 4, not coming into contact with the elastic thread, become somewhat elongated and produce 45 the lacy effect at intervals in the fabric above referred to.

When the top of the stocking formed of the aforesaid alternate drop stitch fabric has been knit to the desired length, the thread feed finger 50 10 is thrown out of operation at knitting station 1, see Fig. 9, and the finger 12 carrying the inelastic or body thread 1a is thrown into operation so as to feed the thread 1a to all of the needles in the next course, as indicated in Fig. 55 17. All of the needles will draw loops of the thread 1a through the loops of the preceding course so that no loops will be caused to cast off and ravel back, as clearly shown in Fig. 17. In the next course formed by the thread 2 and 60 auxiliary cam 18, the thread 2 will be drawn through each of the stitches of the preceding course, thus producing a complete course of stitches on all the needles, and the machine will 65 continue to knit complete courses of stitches with threads 3 and 4 in a single revolution of the cylinder, and thereafter courses of stitches in each revolution of the cylinder throughout the formation of the leg, if the auxiliary knitting cams are allowed to remain in operative position 70 with respect to their respective feed fingers.

It will be obvious that the leg of the stocking can be knit by single courses of knitting with the thread 1a, by throwing out of operation all 75 of the auxiliary cams and their feed fingers, or

the leg may be knit by multiple course knitting with two courses formed simultaneously, by throwing out of operation two of the auxiliary knitting cams and their feed fingers, or the 5 leg may be knit by multiple course knitting with three threads and the formation of three courses in each revolution of the machine by throwing out one of the auxiliary knitting cams and its associated feed finger, as may be preferred.

10 It will also be understood that when the heel pocket is reached, the auxiliary cams and their feed fingers if in use will be thrown out of operation and the heel pocket will be knit by reciprocating knitting and narrowing and widening, in 15 the usual manner, with a single body thread, as the thread *1a*, or a heavier thread or reinforcing thread, which may be thrown in by one of the other thread feed fingers (not shown) in a well known way, after which the foot portion 20 of the stocking between the heel and toe pockets is knit as plain knit fabric by single course or multiple course knitting, as preferred and the toe pocket is formed in the usual manner like the heel pocket.

25 If it is desired, where the leg and foot portions of the stocking are knit by multiple course knitting, the auxiliary knitting cam or cams may be thrown out of operation and one or more courses of single feed stitches may be formed 30 before the heel pocket is knit, and at the conclusion of the heel pocket, and the usual toe joining band may be formed at the end of the foot portion adjacent to the toe pocket by single course knitting, if desired.

35 It will be understood that the alternate drop stitch fabric which forms the top of the stocking may also be knit by single course knitting, in which case courses formed of the elastic thread will be fed to the selected needles, that is to say 40 the alternate needles only at knitting station 1, and the auxiliary cams and their feed guides will be moved out of operative position. After a complete course of alternate stitches has been formed by the elastic thread, the feed of elastic 45 thread is discontinued by throwing out of operation the feed finger *10* and the feed finger *12* is thrown into operation, to knit the intermediate courses of inelastic thread *1a*, which is fed to all the needles at a lower level than the feed- 50 ing position of the finger *10*, as before explained. After the completion of the intervening courses, thread finger *12* is thrown out of operation and finger *10* brought again into operation, to feed the elastic thread to alternate or selected needles, 55 thereby causing the stitches of inelastic thread previously fed to the intervening needles to ravel back, in the manner previously described, so as to produce the alternate drop stitch fabric with the elastic thread in all the wales of separated 60 or spaced courses.

The elastic thread courses may be separated at any desired number of courses, but I have found that a separation of three intervening courses of inelastic thread to be very satisfactory, and this 65 also provides one course of elongated stitches to produce the lacy or open work effect previously referred to.

70 In Fig. 3 I have shown, diagrammatically, the relation of the different threads in the multiple course alternate drop stitch fabric containing, as before described, the elastic thread *1* and the inelastic threads *2*, *3* and *4*. In Fig. 5 I have shown a similar diagrammatical illustration showing the relation of the threads in the alternate drop stitch 75 fabric when formed by single course knitting, in

which there will be only two threads, the elastic thread *1* and the inelastic thread *1a*.

As before indicated, it will be obvious that the alternate drop stitch fabric forming the stocking top may be knit with threads of different colors to produce stripe effects, which is especially facilitated where the fabric is formed by multiple course knitting, and by feeding different colored body yarns at the throat in the usual manner where it is formed by single course knitting. This 10 alternate drop stitch fabric containing the spaced courses of stitches of elastic thread will obviously be of much less diameter than the leg portion *B* of the stocking and will constitute a form fitting top for the stocking. It also has very great 15 elasticity, imparted to it both by the courses of elastic thread and by the necessary looseness of the stitches provided by the floats where the stitches are dropped, so that it can be readily stretched the desired amount to pass it over the 20 heel in drawing on a sock. It is particularly suitable for the top of a short sock or anklet and for children's socks and anklets, as will be readily understood, in the latter of which ornamental effects are particularly desirable. These ornamental effects are provided in part by the elongated 25 stitches produced by intermediate courses of inelastic thread not interknit with the elastic thread as before described, as well as by striping and other effects produced by the use of colored 30 yarns.

It will also be seen that the straightening of the elastic thread courses produces a series of spaced horizontal beads on the inner face of the fabric, as indicated at *r* in Fig. 1, which will indent the 35 skin of the leg or ankle very slightly so as to provide a self-supporting factor, which will hold the stocking, sock or anklet in position on the leg and prevent its slipping down much more efficiently and without the use of a garter. These 40 beads on the inner face of the top are under such light tension when in place on the leg that the wearer is not conscious of them, and experiences no inconvenience therefrom.

The upper edge of the top may be finished by 45 a turned and sewed welt *w*, as shown, or by a single thickness selvage of any usual or preferred type.

It will be understood that in knitting the tubular plain knit alternate drop stitch fabric herein 50 described constituting preferably the form-fitting and self-supporting top of a stocking leg, that any desired thickness of the fabric can be obtained by knitting some or all of the courses formed of inelastic thread, of thread or yarns of 55 desired diameter. Obviously the introduction of one or more heavy yarns will materially increase the body or thickness of the fabric.

I wish it to be understood that in setting up the 60 machine for the formation of my improved fabric or stocking top I may, in some instances, alternate the selected needles (not provided with the shoulders above the butts) to which the elastic thread is fed with two or more non-selected needles (provided with the shoulders above the 65 butts), if this is found desirable. In the following claims where I have used the expression "alternate drop stitch fabric" I include fabric in which the wales are separated a distance equal to a single drop stitch or a plurality of drop stitches. 70

In Fig. 21, for example, which is similar to Fig. 9, I have shown diagrammatically an arrangement of the knitting machine in which the selected needles receiving the elastic thread *1* alternate with two shouldered needles, which do not 75

receive the elastic thread, all the way around the circular series of needles. The operation of the machine will, however, be substantially as previously described. By alternating the selected needles with one, two or more non-selected needles the diameter of the fabric may be slightly varied, as will be readily understood.

In some instances it may be found desirable to feed an additional body thread, indicated at 5 in Figs. 23 to 25, inclusive, in plating relation with the elastic thread to the selected needles at knitting station No. 1, whether alternating with one or more non-selected needles. For this purpose I prefer to provide an auxiliary thread feed finger, indicated at 10a, conveniently located between the previously described thread feed fingers 10 and 12, for feeding the extra body thread 5 to the selected needles only. This thread may be of the same or a different color from the adjacent body threads as preferred. After the fabric leaves the needles, the elastic thread 1 will straighten out due to the tension under which it is fed, in the manner previously described. The additional body thread 5 which will lie parallel to the elastic thread will not be contracted, as will the elastic thread and will form loops 5a projecting slightly from the inner surface of the fabric and forming an ornamental effect in each course containing the elastic thread, which may be utilized advantageously where the top portion is folded outwardly upon itself, in the manner indicated in Fig. 25, as is customary especially in infants' socks and in anklets, and this ornamental effect is enhanced if the thread 5 is of contrasting color with the adjacent threads. Obviously the slack in the thread 5 will not be taken up by the straightening of the elastic thread, as will be the case with the stitches of the preceding and succeeding courses, but when the fabric is stretched in placing it over the leg these ornamental loops will straighten out and permit the stretching of the top to the necessary extent to permit it to be drawn over the heel and placed in proper position on the leg.

45 Where the top is made either of the form of fabric illustrated in Fig. 1, for example, or in Fig. 25, it can be folded outwardly upon itself, as indicated in Fig. 25, in which case the horizontal beads 7 on the exterior fold of the fabric 50 will be brought to the outer face thereof and will contribute an ornamental effect to the fold, while the ribs 7 on the remaining inner fold of the fabric and on the inner face thereof will engage the skin of the wearer and hold the stocking in place on the leg in the manner previously described.

60 It will be seen that in my improved fabric the drop stitch fabric, or as it may be referred to as a ravel stitch fabric, distinguishes clearly from the float thread fabrics, sometimes inaccurately called drop stitch fabrics in which certain needles are thrown out of operation and floats of the knitting thread are drawn straight across between the contiguous stitches, for the purpose of producing an imitation rib fabric of smaller diameter than would be the case if the thread were 65 knit to form a stitch on each needle. In such mock rib fabrics, each float is of substantially the same length as the width of the needle wales, and 70 sinker wales, which it displaces and the fabric has very little stretch laterally, and practically none longitudinally.

75 On the contrary, in my improved fabric each float of the courses containing inelastic thread is of materially greater length than the width of

the needle wales and sinker wales which it displaces because the stitches of the displaced wales are actually formed, and then unraveled with the result that the full amount of thread is fed which would be required to form complete courses of stitches, so that were it not for the courses knit with elastic thread the resulting fabric would have a greater diameter than the normal diameter of the fabric would have if each course contained the complete number of consecutive 10 stitches corresponding with the number of needles of the knitting machine. This additional length of thread in each float which is approximately fifty per cent more than the width of the needle wales and sinker wales it displaces obviously provides the fabric with a much greater capacity to stretch laterally, or in other words to increase its diameter, than regular plain knit fabric, so as to readily permit it to be drawn over the heel where used in the toe of a stocking as 20 here shown.

In the case of the spaced courses formed of elastic thread, said elastic thread is knit only by spaced selected needles and is not knit by intervening needles and unraveled as is the inelastic thread. The elastic courses draw the enlarged fabric together bringing the contiguous wales alongside of each other and slackening the floats of the inelastic thread courses and thus produces a smooth fabric having a much smaller number of stitches than regular plain knitting. Furthermore, as the stitches of elastic thread interlock with stitches formed of inelastic thread in the preceding and succeeding courses, the stitches of elastic thread will straighten out and thereby bring the preceding and succeeding course closer to the elastic thread course as shown and described and this permits the resulting fabric to be stretched longitudinally to a very great extent in some instances nearly one hundred per cent 40 of its normal length when not under distension in either direction, as will be readily understood.

What I claim and desire to secure by Letters Patent is:

1. A tubular plain knit alternate drop stitch 45 fabric comprising courses composed of inelastic thread the stitches of which are connected by floats of materially greater length than the width of the needle wales and sinker wales which they displace and having spaced courses composed 50 entirely of elastic thread under sufficient tension to draw the adjacent wales of said alternate drop stitch fabric into close proximity to reduce the diameter of the fabric and produce a smooth exterior surface.

2. A tubular plain knit alternate drop stitch fabric comprising courses composed of inelastic thread the stitches of which are connected by floats of materially greater length than the width of the needle wales and sinker wales which they displace and having spaced courses composed 60 entirely of elastic thread under sufficient tension to straighten out the stitches of said elastic thread course, and draw the adjacent wales of said alternate drop stitch fabric into close proximity to 65 reduce the diameter of the fabric and produce a smooth exterior surface, the elastic thread projecting on the inner face of the fabric and forming a series of spiral beads to support the fabric against longitudinal movement on a body mem- 70 ber.

3. A tubular plain knit alternate drop stitch fabric comprising courses composed of inelastic thread the stitches of which are connected by floats of materially greater length than the width 75

of the needle wales and sinker wales which they displace and having spaced courses composed entirely of elastic thread the stitches of which are connected by floats of a length substantially the same as the width of the needle wales and sinker wales which they displace, said elastic thread under sufficient tension to draw the adjacent wales of said alternate drop stitch fabric into close proximity to reduce the diameter of the fabric and produce a smooth exterior surface, the stitches of the elastic thread courses being interknit with the stitches of a preceding and succeeding course of non-elastic thread, and the elastic thread being straightened out and thereby 10 distorting the stitches of said preceding and succeeding courses and drawing them into close relation in the fabric.

4. A tubular plain knit alternate drop stitch fabric comprising courses composed of inelastic thread the stitches of which are connected by floats of materially greater length than the width of the needle wales and sinker wales which they displace and having spaced courses composed entirely of elastic thread the stitches of which are connected by floats of a length substantially the same as the width of the needle wales and sinker wales which they displace, said elastic thread under sufficient tension to draw the adjacent wales of said alternate drop stitch fabric into close proximity to reduce the diameter of the fabric and produce a smooth exterior surface, the stitches of the elastic thread courses being interknit with the stitches of a preceding and succeeding course of non-elastic thread, and the elastic thread being straightened out and thereby 20 distorting the stitches of said preceding and succeeding courses and drawing them into close relation in the fabric, said fabric having additional undistorted courses of stitches, of inelastic thread, between the courses which are interknit with the elastic thread and which produce an ornamental open work effect.

5. A stocking having a tubular plain knit alternate drop stitch top comprising courses composed of inelastic thread the stitches of which are connected by floats of substantially the same length as the length of yarn in the needle wales and sinker wales which they displace and spaced courses composed entirely of elastic thread under tension sufficient to straighten out the stitches of said elastic course and draw the adjacent wales of said alternate drop stitch fabric into close proximity to reduce the diameter of the fabric and produce a smooth exterior surface, and an integral leg portion of plain knitting formed of inelastic thread having a materially greater number of stitches in each course as the courses of the top, alternate wales of said leg portion being continuous with wales of the alternate drop 30 stitch top.

6. A stocking having a tubular plain knit alternate drop stitch top comprising courses composed of inelastic thread the stitches of which are connected by floats of substantially the same length as the length of yarn in the needle wales and sinker wales which they displace and spaced courses composed entirely of elastic thread under sufficient tension to straighten out the stitches of said elastic course and draw the adjacent wales of said alternate drop stitch fabric into close proximity to reduce the diameter of the fabric and produce a smooth exterior surface, and an integral leg portion of plain knitting formed of inelastic thread having twice the number of stitches in each course as the courses of the top, alternate 40

wales of said leg portion being continuous with wales of the alternate drop stitch top, the elastic thread in said top projecting on the inner face of the fabric and forming a series of spiral beads to support the leg of the stocking in use.

7. A stocking having a tubular plain knit alternate drop stitch top comprising courses composed of inelastic thread the stitches of which are connected by floats of substantially the same length as the length of yarn in the needle wales and sinker wales which they displace and spaced courses composed entirely of elastic thread under sufficient tension to straighten out the stitches of said elastic course, and draw the adjacent wales of said alternate drop stitch fabric into close proximity to reduce the diameter of the fabric and produce a smooth exterior surface, and an integral leg portion of plain knitting formed of inelastic thread having twice the number of stitches in each course as the courses of the top, alternate wales of said leg portion being continuous with wales of the alternate drop stitch top, the stitches of said elastic thread courses of the top being interknit with the stitches of a preceding and succeeding course of non-elastic thread which are distorted by the straightening of the elastic thread to bring said interknit inelastic courses into close proximity.

8. A stocking having a tubular plain knit alternate drop stitch top comprising courses composed of inelastic thread the stitches of which are connected by floats of substantially the same length as the length of yarn in the needle wales and sinker wales which they displace, said elastic thread being under sufficient tension to straighten out the stitches of said elastic thread course, and draw the adjacent wales of said alternate drop stitch fabric into close proximity to reduce the diameter of the fabric and produce a smooth exterior surface, and an integral leg portion of plain knitting formed of inelastic thread having twice the number of stitches in each course as the courses of the top, alternate wales of said leg portion being continuous with wales of the alternate drop stitch top, the stitches of said elastic thread courses of the top being interknit with the stitches of a preceding and succeeding course of non-elastic thread which are distorted by the straightening of the elastic thread to bring said interknit inelastic courses into close proximity, and said top having additional alternate drop stitch courses of inelastic thread between said preceding and succeeding courses which are undistorted and produce an open work effect.

9. A tubular plain knit alternate drop stitch fabric comprising courses composed of inelastic thread the stitches of which are connected by floats of materially greater length than the width of the needle wales and sinker wales which they displace and spaced courses composed entirely of elastic thread under sufficient tension to straighten out the stitches of said elastic thread course, and draw the wales of said drop stitch fabric into close proximity to reduce the diameter of the fabric and produce a smooth exterior surface, the stitches of each course of said fabric being interknit with a preceding course and a succeeding course formed of a different thread.

10. A tubular plain knit alternate drop stitch fabric comprising courses composed of inelastic

thread the stitches of which are connected by floats of materially greater length than the width of the needle wales and sinker wales which they displace and spaced courses composed entirely of 5 elastic thread the stitches of which are connected by floats of a length substantially the same as the width of the needle wales and sinker wales which they displace, said elastic thread being under sufficient tension to draw the wales of said 10 drop stitch fabric into close proximity to reduce the diameter of the fabric and produce a smooth exterior surface, the stitches of each course of said fabric being interknit with a preceding course and a succeeding course formed of a different 15 thread, the elastic thread projecting on the inner face of the fabric and forming a series of spiral beads to hold the fabric from longitudinal movement on a body member.

11. A tubular plain knit alternate drop stitch 20 fabric comprising courses composed of inelastic thread the stitches of which are connected by floats of materially greater length than the width of the needle wales and sinker wales which they displace and spaced courses composed entirely of 25 elastic thread the stitches of which are connected by floats of a length substantially the same as the width of the needle wales and sinker wales which they displace, said elastic thread being under sufficient tension to straighten out the stitches 30 of said elastic thread course, and draw the wales of said drop stitch fabric into close proximity to reduce the diameter of the fabric and produce a smooth exterior surface, the stitches of each course of said fabric being interknit with a preceding course and a succeeding course formed of a different 35 thread, the stitches of the elastic thread courses being interknit with the stitches of a preceding and succeeding course of inelastic thread which are distorted by the straightening of the elastic thread and thereby brought into 40 close relation.

12. A tubular plain knit alternate drop stitch 45 fabric comprising courses composed of inelastic thread the stitches of which are connected by floats of materially greater length than the width of the needle wales and sinker wales which they displace and spaced courses composed entirely of elastic thread the stitches of which are connected by floats of a length substantially the 50 same as the width of the needle wales and sinker wales which they displace, said elastic thread being under sufficient tension to straighten out the stitches of said elastic thread course, and draw the wales of said drop stitch fabric into close 55 proximity to reduce the diameter of the fabric and produce a smooth exterior surface, the stitches of each course of said fabric being interknit with a preceding course and a succeeding course formed of a different thread, the stitches of the elastic thread courses being interknit with the 60 stitches of a preceding and succeeding course of inelastic thread which are distorted by the straightening of the elastic thread and thereby brought into close relation, said fabric having 65 additional courses of stitches of inelastic thread between the courses interknit with the elastic thread and produce an open work fabric.

13. A stocking having a tubular plain knit alternate drop stitch top comprising courses composed 70 of inelastic thread the stitches of which are connected by floats of materially greater length than the width of the needle wales and sinker wales which they displace and spaced courses composed entirely of elastic thread the 75 stitches of which are connected by floats of a

length substantially the same as the width of the needle wales and sinker wales which they displace, said elastic thread being under sufficient tension to straighten out the stitches of said elastic thread course, and draw the adjacent wales 5 of said alternate drop stitch fabric into close proximity to reduce the diameter of the fabric and produce a smooth exterior surface, and an integral leg portion of plain knitting formed of inelastic thread having a greater number of stitches 10 in each course as the courses of the top, alternate wales of said leg portion being continuous with wales of the alternate drop stitch top, the stitches of each course of said top and of said leg portion being interknit with a preceding and 15 succeeding course formed of a separate thread.

14. A stocking having a tubular plain knit alternate drop stitch top comprising courses composed of inelastic thread the stitches of which are connected by floats of materially greater length 20 than the width of the needle wales and sinker wales which they displace and spaced courses composed entirely of elastic thread the stitches of which are connected by floats of a length substantially the same as the width of the needle 25 wales and sinker wales which they displace, said elastic thread being under sufficient tension to straighten out the stitches of said elastic thread course, and draw the adjacent wales of said alternate drop stitch fabric into close proximity to 30 reduce the diameter of the fabric and produce a smooth exterior surface, and an integral leg portion of plain knitting formed of inelastic thread having twice the number of stitches in each course as the courses of the top, alternate wales 35 of said leg portion being continuous with wales of the alternate drop stitch top, the stitches of each course of said top and of said leg portion being interknit with a preceding and succeeding course formed of a separate thread, and said 40 elastic thread projecting on the inner face of said alternate drop stitch fabric top and forming a series of spiral beads to support the leg of the stocking.

15. A stocking having a tubular plain knit 45 alternate drop stitch top comprising courses composed of inelastic thread the stitches of which are connected by floats of materially greater length than the width of the needle wales and sinker wales which they displace and spaced 50 courses composed entirely of elastic thread the stitches of which are connected by floats of a length substantially the same as the width of the needle wales and sinker wales which they displace, said elastic thread being under sufficient 55 tension to straighten out the stitches of said elastic thread course, and draw the adjacent wales of said alternate drop stitch fabric into close proximity to reduce the diameter of the fabric and produce a smooth exterior surface, and an integral leg portion of plain knitting formed of inelastic thread having twice the number of 60 stitches in each course as the courses of the top, alternate wales of said leg portion being continuous with wales of the alternate drop stitch 65 top, the stitches of each course of said top and of said leg portion being interknit with a preceding and succeeding course formed of a separate thread, the elastic thread in said alternate drop 70 stitch top lying in substantially straight lines across the fabric, distorting the stitches of the preceding and succeeding courses of inelastic thread and drawing said courses into close proximity.

16. A stocking having a tubular plain knit 75

5 alternate drop stitch top comprising courses composed of inelastic thread the stitches of which are connected by floats of materially greater length than the width of the needle wales and sinker

6 wales which they displace and spaced courses composed entirely of elastic thread the stitches of which are connected by floats of a length substantially the same as the width of the needle wales and sinker wales which they displace, said

10 elastic thread being under sufficient tension to straighten out the stitches of said elastic thread course, and draw the adjacent wales of said alternate drop stitch fabric into close proximity to reduce the diameter of the fabric and produce a

15 smooth exterior surface, and an integral leg portion of plain knitting formed of inelastic thread having twice the number of stitches in each course as the courses of the top, alternate wales of said leg portion being continuous with wales of the

20 alternate drop stitch top, the stitches of each course of said top and of said leg portion being interknit with a preceding and succeeding course formed of a separate thread, the elastic thread in

25 said alternate drop stitch top lying in substantially straight lines across the fabric, distorting the stitches of the preceding and succeeding courses of inelastic thread and drawing said courses into close proximity, and said alternate drop stitch fabric top having additional courses

30 of stitches of inelastic thread between the courses interknit with the elastic thread which are not distorted, and producing an open work effect.

17. A tubular plain knit alternate drop stitch fabric comprising courses composed of inelastic

35 thread the stitches of which are connected by floats of substantially the same length as the length of yarn in the needle wales and sinker wales which they displace and having spaced courses composed entirely of elastic thread the

40 stitches of which are connected by floats of a length substantially the same as the width of the needle wales and sinker wales which they displace, said elastic thread being under sufficient tension to straighten out the stitches of said

45 elastic thread course and draw the adjacent wales of said alternate drop stitch fabric into close proximity to reduce the diameter of the fabric and produce a smooth exterior surface, all of the courses intervening the elastic thread courses being continuous and composed of the same in-

50 elastic thread.

18. A tubular plain knit alternate drop stitch fabric comprising courses composed of inelastic

55 thread the stitches of which are connected by floats of substantially the same length as the length of yarn in the needle wales and sinker wales which they displace and having spaced courses composed entirely of elastic thread the

60 stitches of which are connected by floats of a length substantially the same as the width of the needle wales and sinker wales which they displace, said elastic thread being under sufficient tension to straighten out the stitches of said elastic thread course and draw the adjacent wales

65 of said alternate drop stitch fabric into close proximity to reduce the diameter of the fabric and produce a smooth exterior surface, the elastic thread projecting on the inner face of the fabric and forming a series of spiral beads to support

70 the fabric against longitudinal movement on a body member, all of the courses intervening the elastic thread courses being continuous and composed of the same inelastic thread.

19. A tubular plain knit alternate drop stitch fabric comprising courses composed of inelastic thread the stitches of which are connected by floats of materially greater length than the width of the needle wales and sinker wales which they displace and having spaced courses composed entirely of elastic thread under sufficient tension to draw the adjacent wales of said alternate drop stitch fabric into close proximity to reduce the diameter of the fabric and produce a smooth exterior surface, the stitches of the elastic thread courses being interknit with the stitches of a preceding and succeeding course of non-elastic thread, and the elastic thread being straightened out and thereby distorting the stitches of said preceding and succeeding courses and drawing them into close relation in the fabric, all of the courses intervening the elastic thread courses being composed of the same inelastic thread.

20. A tubular plain knit alternate drop stitch 20

fabric comprising courses composed of inelastic thread the stitches of which are connected by floats of substantially the same length as the length of yarn in the needle wales and sinker wales which they displace and having spaced 25

courses composed entirely of elastic thread the stitches of which are connected by floats of a length substantially the same as the width of the needle wales and sinker wales which they displace, said elastic thread being under sufficient 30

tension to straighten out the stitches of said elastic thread course, and draw the adjacent wales of said alternate drop stitch fabric into close proximity to reduce the diameter of the fabric and produce a smooth exterior surface, said 35

fabric having additional undistorted courses of stitches of inelastic thread between the courses which are interknit with the elastic thread and which produce an ornamental open work effect, all of the courses intervening the elastic thread 40

courses being continuous and composed of the same inelastic thread.

21. A tubular plain knit alternate drop stitch fabric, comprising courses composed of inelastic

45 thread the stitches of which are connected by floats of substantially the same length as the length of yarn in the needle wales and sinker wales which they displace and having spaced courses formed of elastic thread and an inelastic

50 thread, said elastic thread being under sufficient tension to draw the adjacent wales of said fabric into close proximity to reduce the diameter of the fabric and produce a smooth exterior surface.

22. A tubular plain knit alternate drop stitch fabric, comprising courses of inelastic thread the 55

stitches of which are connected by floats of substantially the same length as the length of yarn in the needle wales and sinker wales which they displace and having spaced courses the stitches of which are composed of inelastic and elastic 60

threads in plating relation connected by floats of a length substantially the same as the width of the needle wales and sinker wales which they displace, the elastic thread being under sufficient

65 tension to straighten out the stitches of said elastic thread course, and draw the adjacent wales of said fabric into close proximity to reduce the diameter of the fabric and produce a smooth exterior surface, and said plating thread between the stitches of the courses containing the elastic 70

thread being formed into ornamental loops by the contraction of the elastic thread.
